FLUID PRESSURE OPERATED SCALE

Eugene L. Kilbourn, Marshall, Mich., assignor to
Progressive Dynamics, Inc., Marshall, Mich.

Filed Oct. 14, 1966, Ser. No. 4,273

Term of patent 7 years

(Cl. D52—10)

FIG. 1

FIG. 2

FIG. 5

FIG. 3

FIG. 4

FIG. 6

FIG. 1 is a front and left side perspective view of a fluid pressure operated scale showing my new design;

FIG. 2 is a front elevational view;

FIG. 3 is a rear elevational view;

FIG. 4 is a left side elevational view, the right side being a mirror image thereof;

FIG. 5 is a top plan view; and

FIG. 6 is a bottom view.

The essential features of the design are shown in full lines.

I claim:

The ornamental design for a fluid pressure operated scale, as shown and described.
